SEMICONDUCTOR INTERNAL COMBUSTION
ENGINE IGNITION SYSTEMRichard L. Konopa, Anderson, Ind., assignor to General
Motors Corporation, Detroit, Mich., a corporation of
DelawareFiled Dec. 20, 1963, Ser. No. 332,012
9 Claims. (Cl. 307—88.5)

This invention relates to a semiconductor internal combustion engine ignition system and more particularly to an ignition system that uses a unijunction transistor as an active element in the ignition system.

The ignition system to be described is in some respects similar to the ignition systems shown in the Konopa Patent 3,087,090, and in the Short et al. Patent 3,087,001.

The above-mentioned Konopa and Short, et al. patents disclose semiconductor ignition systems wherein a transistor controls primary winding current. In these systems, resistor-capacitor coupling is used between certain transistor stages. Although the systems illustrated in Short, et al. and Konopa perform satisfactorily, it has been found that improved low-speed triggering can be achieved if the triggering of the system can be made independent of the rate of change of magnetic pick-up voltage.

It accordingly is one of the objects of this invention to provide a semiconductor ignition system wherein improved triggering of the system is achieved at low engine speeds.

Another object of this invention is to provide a semiconductor ignition system wherein the amount of voltage required to trigger the system is decreased as compared to known systems.

Still another object of this invention is to provide a transistor ignition system which includes a plurality of transistors and wherein at least one of these transistors is a unijunction transistor.

Another object of this invention is to provide a transistor ignition system of the breakerless type which uses a plurality of transistors one of which is a unijunction transistor.

Further objects and advantages of the present invention will be apparent from the following description, reference being had to the accompanying drawings wherein preferred embodiments of the present invention are clearly shown.

The single figure drawing is a schematic circuit diagram of an ignition system made in accordance with this invention.

Referring now to the drawing, the reference numeral 10 designates an internal combustion engine having a plurality of spark plugs 12. The spark plugs are connected with conductors 14 which in turn are connected with the electrodes or inserts 16 of a distributor cap 18. The electrodes 16 are insulated from each other by the insulating material of the distributor cap and these electrodes or inserts cooperate with a rotor contact 20 which is driven by the engine 10 and which serves to distribute spark energy to the electrodes 16 from a conductor 22.

The source of direct current for the ignition system takes the form of a battery 24, one side of which is grounded. The opposite side of the battery is connected with an ignition switch 26 and when switch 26 is closed, battery voltage is applied across power supply conductors 28 and 30. It will be appreciated that on a motor vehicle, the conductors 28 and 30 can also be supplied by a generator which has a direct current output.

The control mechanism for controlling ignition firing is a magnetic pick-up generally designated by reference numeral 32. This magnetic pick-up has a rotor 34 that is formed of magnetic material. The rotor 34 and the rotor contact 20 are synchronized in their rotation and are both driven by the engine 10.

The rotor 34 has four arms which rotate relative to a U-shaped part 36 which is formed of magnetic material. A pick-up coil 38 is wound on one leg of the U-shaped part and a permanent magnet 40 is provided for causing a flowing of magnetic flux through the U-shaped part when the pole tips of the rotor 34 are aligned with the ends of the U-shaped part. It will be appreciated that as the rotor 34 rotates, pulses of voltage are induced in the pick-up coil 38 which have a predetermined spacing. The frequency of these pulses of voltage depends upon the speed of rotation of the rotor 34 and therefore depends upon engine speed. The pulses of voltage go positive and negative with periods of no voltage output between the positive and negative pulses.

10 The ignition system has an NPN transistor 42. The base of transistor 42 is connected with junction 44 located between pick-up coil 38 and resistor 46. The resistor 46 and the pick-up coil 38 are connected in series across power conductors 28 and 30.

15 The emitter of transistor 42 is connected directly with grounded conductor 30 whereas the collector of transistor 42 is connected with junction 48. A resistor 50 connects the junction 48 and the power conductor 28.

20 The junction 48 is connected with the emitter of a unijunction transistor 52. This unijunction transistor has a base B₂ and another base B₁. The base B₂ of the unijunction transistor is connected with power conductor 28. The base B₁ of the unijunction transistor is connected with junction 54 and this junction is connected to power conductor 30 by a resistor 56.

25 The unijunction transistor as is known to those skilled in the art, can be formed from a silicon bar which has spaced ohmic contacts which are connected with the base B₂ and the base B₁. The emitter electrode is connected with a junction on the silicon bar. The characteristics of this transistor are such that the resistance between the emitter and the base B₁ decreases as the emitter current increases.

30 The junction 54 is connected with the base of an NPN transistor 58. A resistor 60 connects the collector of transistor 58 with power conductor 28. The emitter of transistor 58 is connected with junction 62. A resistor 64 is connected between junction 62 and the grounded power conductor 30.

35 The junction 62 is connected with the base of an NPN transistor 66. The emitter of transistor 66 is connected to power conductor 30 while the collector of transistor 66 is connected to one side of the primary winding 68 of an ignition coil designated by reference numeral 70. The opposite side of the primary winding 68 is connected with conductor 28 at junction 74.

40 The secondary winding of the ignition transformer is designated by reference numeral 72. One side of this secondary winding is connected with junction 74 and therefore to one side of the primary winding 68. The opposite side of the secondary winding 72 is connected to the conductor 22 to feed the spark plugs 12 via rotor contact 20, electrodes 16, and spark plug leads 14.

45 When the ignition switch 26 is closed, the voltage of the direct current source 24 is impressed across conductors 28 and 30. If the engine 10 is now being cranked by a starting motor or if it is running, the rotor 34 will rotate and a train of voltage pulses will be induced in the pick-up coil 38.

50 When there is no voltage induced in the pick-up coil 38, the voltage at junction 48 and on the emitter of unijunction transistor 52 is sufficient to cause the unijunction transistor 52 to conduct. Transistor 42 at this time is slightly conductive since its base is biased positive with respect to its emitter by source 24 and the voltage at junction 48 is sufficiently positive to bias transistor 52 conductive due to the voltage developed across slightly

conductive transistor 42. With unijunction transistor 52 conductive, the junction 54 is positive with respect to conductor 30 and transistor 58 is therefore biased to a conductive condition between its collector and emitter. Since transistor 58 is conductive, the junction 62 will be positive with respect to conductor 30 and this applies a forward bias to transistor 66 to switch it on between its collector and emitter. Since transistor 66 is conductive, current can flow from conductor 28, through primary winding 68 and through the collector-emitter circuit of transistor 66 to the negative grounded conductor 30.

To summarize, it is seen that with no voltage pulse induced in the pick-up coil 38, transistor 42 is slightly conductive and transistors 52, 58 and 66 are all biased to a conductive condition.

When a voltage of the proper polarity is induced in pick-up coil 38, the base of transistor 42 is driven more positive than its emitter and is driven more positive than the bias it receives from battery 24 when no voltage is induced in pick-up coil 38. This increases the conduction of transistor 42 in its collector-emitter circuit and the voltage drop across resistor 50 tends to drive the junction 48 negative with respect to conductor 28. The voltage of junction 48 falls to a point where the unijunction transistor 52 now becomes nonconductive. When this happens, the voltage of junction 54 is reduced to a point where transistor 58 becomes nonconductive in its collector-emitter circuit. When transistor 58 goes nonconductive, the voltage of junction 62 approaches that of conductor 30 and the transistor 66 is therefore now biased to a nonconductive condition. When transistor 66 shuts off in its collector-emitter circuit, the primary circuit for the ignition system is interrupted and current can no longer flow through primary winding 68. As a result, a high voltage is induced in secondary winding 72 which is applied to one of the spark plugs via conductor 22, rotor contact 20, one of the electrodes 16 and then through one of the spark plug wires 14. The rotor contact 20 and rotor 34 are so synchronized in their rotation that the high voltage is induced in secondary winding 72 at a time that the rotor contact 20 is passing by one of the electrodes 16.

When a voltage is induced in the pick-up coil 38 of a polarity which drives the emitter of transistor 42 positive, to thereby bias the transistor 42 nonconductive, the operation of the system is the same as when there is no output voltage developed in the coil 38. This is because when the transistor 42 is only slightly conductive or nonconductive, the voltage of junction 48 is increased and approaches that of conductor 28 to bias transistor 52 conductive. Whenever transistor 52 is conductive, the transistors 58 and 66 are biased conductive as explained hereinbefore.

By using the unijunction transistor 52 and by eliminating resistor-capacitor coupling, the low speed triggering of the ignition system is improved and less voltage from coil 38 is required to trigger the system as compared to systems that use resistor-capacitor coupling.

Although the ignition system as disclosed is to be used with a four cylinder engine, it could be used with engines having a number of cylinders other than four by changing the number of arms on rotor 34 and by changing the number of electrodes for distributor cap 18. The magnetic pick-up 32, the distributor cap 18 and the rotor contact 20 can be built into one unit if so desired.

Transistors 42, 58 and 66 have all been shown as being of the NPN type. These transistors could be PNP transistors if desired.

While the embodiments of the present invention as herein disclosed, constitute a preferred form, it is to be understood that other forms might be adopted.

What is claimed is as follows:

1. An ignition control circuit for an internal combustion engine ignition system comprising, a magnetic pick-up having an output coil, a source of direct current, a transistor having emitter, collector and base electrodes,

means connecting the emitter and collector electrodes of said transistor across said source of direct current, means connecting said output coil across the emitter and base electrodes of said transistor, a unijunction transistor having an emitter, a first base and a second base, means connecting said first base and second base of said unijunction transistor across said source of direct current, an output circuit connected with said unijunction transistor for controlling the current flow through the primary winding of an ignition coil, and means connecting the emitter of said unijunction transistor with the collector of said transistor.

2. A control circuit for controlling an internal combustion ignition system comprising, a source of direct current, a magnetic pick-up having a coil winding in which pulses of voltage are induced, an output terminal adapted to control the primary circuit of an ignition system, a transistor having emitter, collector and base electrodes, means connecting the emitter and collector electrodes of said transistor across said source of direct current, means connecting said output coil across the emitter and base electrodes of said transistor, a unijunction transistor having first and second base electrodes and an emitter electrode, means connecting said first and second base electrodes of said unijunction transistor across said source of direct current, means connecting said output terminal with said unijunction transistor, and means connecting the emitter of said unijunction transistor with the collector of said transistor.

3. A control circuit comprising, a source of direct current, a unijunction transistor having first and second base electrodes and an emitter electrode, a second transistor having emitter, collector and base electrodes, a first circuit connected across said source of direct current including said first and second base electrodes of said unijunction transistor, an output terminal for said control circuit connected with one of the base electrodes of said unijunction transistor, a second circuit connected across said source of direct current including a resistor and the emitter and collector electrodes of said second transistor, means connecting the junction of said resistor and one of said emitter and collector electrodes of said transistor with the emitter of said unijunction transistor, means connecting the base electrode of said transistor with said source of direct current in such a manner that said transistor is normally biased at least partially "on" by said source of direct current, and a source of pulsating voltage connected across the emitter and base electrodes of said transistor for periodically driving the transistor fully conductive between its emitter and collector electrodes.

4. A control circuit for controlling an internal combustion engine ignition system comprising, a source of direct current, a unijunction transistor having first and second base electrodes and an emitter electrode, a transistor having emitter, collector and base electrodes, a magnetic pick-up having an output coil in which pulses of voltage are induced, first, second and third parallel circuits connected across said source of direct current, said first circuit including a resistor and said output coil, said second circuit including the emitter and collector electrodes of said transistor, said third circuit including said first and second base electrodes of said unijunction transistor, means connecting the base electrode of said transistor between one side of said resistor and said coil winding, and means connecting one of said emitter and collector electrodes of said transistor with the emitter of said unijunction transistor.

5. An ignition system for an internal combustion engine comprising, an ignition coil having a primary winding and a secondary winding, a source of direct current, a first transistor having emitter, collector and base electrodes, means connecting the emitter and collector electrodes of said first transistor and said primary winding in series across said source of direct current, a second transistor having emitter, collector and base electrodes, means connecting the emitter and the collector electrodes of said second transistor across said source of direct current, means connecting the emitter electrode of said second

transistor with base electrode of said first transistor, a unijunction transistor having first and second bases and an emitter, means connecting said first and second bases of said unijunction transistor across said source of direct current, means connecting one of the bases of said unijunction transistor with the base of said second transistor, a third transistor having emitter, collector and base electrodes, means connecting the emitter and collector electrodes of said third transistor across said source of direct current, means connecting the emitter of said unijunction transistor with the collector of said third transistor, and timing means operated in synchronism with said engine for controlling the conduction of said third transistor.

6. The ignition system according to claim 5 wherein the timing means is a magnetic pick-up having an output coil connected across the emitter and base electrodes of said third transistor.

7. An ignition system for an internal combustion engine comprising, a source of direct current, an ignition coil having a primary winding and a secondary winding, a unijunction transistor having an input circuit and an output circuit, means connected with the output circuit of said unijunction transistor for controlling current flow through said primary winding of said ignition coil, a magnetic pick-up having an output coil, and means connecting said output coil with the input circuit of said unijunction transistor, said unijunction transistor being connected across said source of direct current, said source of direct current feeding the primary winding of said ignition coil.

8. An ignition system for an internal combustion engine comprising, a source of direct current, an ignition coil having a primary winding and a secondary winding, a control circuit connected to said primary winding and with said source of direct current for controlling current flow through said primary winding, a timing circuit driven in synchronism with said engine, a unijunction transistor having first and second bases connected across said source of direct current and having an emitter, means connecting the emitter and one of the bases of said unijunction transistor with said timing circuit, and means connecting said one base of said unijunction transistor with said control circuit.

9. An ignition system for an internal combustion engine comprising, a source of direct current, an ignition coil having a primary winding and a secondary winding, a control transistor, means connecting said control transistor and said primary winding in series across said source of direct current, said control transistor switching on and off to control primary winding current, a voltage pulse generator having an output coil, and a circuit coupling said output coil and the emitter and base electrodes of said control transistor for applying control signals to said control transistor, said circuit including at least one unijunction transistor.
